No. 690,261.

Patented Dec. 31, 1901.

J. C. FLINT & M. S. DEAN.

SWITCH.

(Application filed June 18, 1901.)

(No Model.)

UNITED STATES PATENT OFFICE.

JOHN C. FLINT AND MAURICE S. DEAN, OF ANACONDA, MONTANA.

SWITCH.

SPECIFICATION forming part of Letters Patent No. 690,261, dated December 31, 1901.

Application filed June 18, 1901. Serial No. 65,015. (No model.)

To all whom it may concern:

Be it known that we, JOHN C. FLINT and MAURICE S. DEAN, citizens of the United States, and residents of Anaconda, in the 5 county of Deerlodge and State of Montana, have invented certain new and useful Improvements in Switches, of which the following is a full, clear, and exact description.

The object of the invention is to provide 10 certain new and useful improvements in switches, whereby the life of the switch-point is greatly lengthened and when the switch is located on a curve the danger of the wheels climbing the switch-point is completely prevented.

The invention consists of novel features and parts and combinations of the same, as will be fully described hereinafter and then pointed out in the claims.

20 A practical embodiment of the invention is represented in the accompanying drawings, forming a part of this specification, in which similar characters of reference indicate corresponding parts in both the views.

25 Figure 1 is a plan view of the improvement as applied, and Fig. 2 is an edge view of the head-rod.

The lead-rail A and the switch-rail B are connected with each other by rods C and D, 30 of which the latter is the head-rod and is connected in the usual manner by a link E with the switch-changing mechanism for opening or closing the switch in the usual manner. The end of the lead-rail A terminates near 35 the end of the guard-rail F, while the end B' of the switch-rail B is extended beyond the end of the lead-rail A, so as to be located opposite a portion of the guard-rail F, as is plainly indicated in Fig. 1. This extension of the

40 switch-rail B is connected by an extension-rod D' with the head-rod D, said extension-rod D' being connected with a plate G, bolted to the extension of the switch-rail, and said extension-rod D' is provided with a turnbuckle D² for lengthening or shortening the extension-rod and allowing the trackman to properly adjust the extension or point B' of the switch-rail B to existing conditions of the track-rails. Now it is evident that by 45 50 the arrangement described the extension of

the switch-rail B is completely protected against injury from the car-wheels, as the guard-rail F will not allow the wheels to injure said extension. Furthermore, it is evident that when the switch is closed the car-wheels are not liable to climb the switch-point or go between the point-rail and the turnout-rail, thus avoiding wrecking the train. It is understood that by the guard-rail F protecting the switch-point it is evident that the latter will last as long as the main rail, and consequently its life is greatly increased over the ordinary switch-points as now used.

Having thus fully described our invention, 65 we claim as new and desire to secure by Letters Patent—

1. A switch having a switch-rail, the point of which extends beyond the ends of the opposite lead-rail, the extending point being 70 provided with a brace, as set forth.

2. A switch having a guard-rail, and an opposite switch-rail, the point of which extends opposite the end portion of said guard-rail, the extending point being provided with 75 a brace, as set forth.

3. A switch having a switch-rail, the point of which extends beyond the ends of the opposite lead-rail, and a head-rod for the switch and lead-rails and having an extension for 80 connection with said extension-point, as set forth.

4. A switch having a switch-rail, the point of which extends beyond the ends of the opposite lead-rail, a head-rod for the switch and 85 lead-rails and having an extension for connection with said extension-point, and a turnbuckle in said extension, for lengthening or shortening the same, as set forth.

5. A switch, comprising a switch-rail and 90 lead-rail, of which the point of the switch-rail extends beyond the lead-rail, and means for independently adjusting the said extending point in a lateral direction relatively to the body or remainder of said switch-rail.

JOHN C. FLINT.
MAURICE S. DEAN.
